UNITED STATES PATENT OFFICE.

DANIEL R. SCHOLES, OF CHICAGO, ILLINOIS, ASSIGNOR TO AERMOTOR COMPANY, OF CHICAGO, ILLINOIS, A CORPORATION OF ILLINOIS.

WINDMILL.

Application filed March 25, 1924. Serial No. 701,720.

To all whom it may concern:

Be it known that I, DANIEL R. SCHOLES, a citizen of the United States, residing at Chicago, in the county of Cook and the State of Illinois, have invented a certain new and useful Improvement in Windmills, of which the following is a full, clear, concise, and exact description.

My invention relates to windmills. In 10 one of its characteristics, the invention resides in an improved bearing for relatively rotating parts of the windmill. In another of its characteristics, the invention resides in the provision of means for protecting 15 relatively movable parts from the weather.

The invention is of particular service in connection with the windmill shown in the patent issued to La Verne Noyes, December 14, 1915, No. 1,163,682, though the invention 20 is not to be limited to such employment.

The windmill of the aforesaid patent contains a furling device that is inclusive of a manually adjustable vertically reciprocable nonrotating sleeve that surrounds a stationary upright column, a collar rotatable upon and vertically reciprocable with said sleeve, and linkage between the collar and the mill vane whereby the vane may be folded toward the wheel when the wheel is 25 to be placed out of the wind. In northern latitudes the collar of such a windmill was apt to be frozen against movement, in cold weather. This was due to the wide access that existed to the collar. In carrying out 30 my invention, the vertically reciprocable nonrotating sleeve carries an annular hood which overhangs the collar in a manner to direct rain and snow away from its interior. The collar, in turn, carries an annular hood 35 which guards against seepage to the sleeve.

In the preferred embodiment of the invention, the portion of the sleeve which is overhung by the annular hood upon the collar is in the form of a rim of an annular 40 lubricant receiving trough that preferably merely rests upon the sleeve, the trough being in effect, a part of the sleeve as the trough is not normally movable with respect thereto, due to the friction between the bottom of the trough and the engaging adjacent horizontal end face of the sleeve. The collar is seated upon the bottom of the trough which, with the oil or other lubricant in it,

constitutes an antifriction step bearing for the collar. 55

The invention will be more fully explained in connection with the accompanying drawings showing one type of windmill equipped in accordance with the preferred embodiment of the invention. Fig. 1 is a view, in elevation, of such a windmill; Fig. 2 is a sectional view on line 2—2 of Fig. 1; Fig. 3 is a sectional view on line 3—3 of Fig. 1; Fig. 4 is a view, on a larger scale, of a part of the structure appearing in Fig. 3; 65 and Fig. 5 is a sectional view on line 5—5 of Fig. 4.

Like parts are indicated by similar characters of reference throughout the different figures. 70

The wind wheel 1, having a horizontal axis, is mounted upon a shaft which carries spur pinions in mesh with spur gears 3 that operate pitmen 4 having connection at their upper ends with the load rod 5. 75 The wind wheel is mounted upon a mill head 6 which is afforded an upright axis of rotation by being mounted upon the shouldered end of a stationary vertical column in the form of a pipe 7 at the upper 80 end of the mill tower and through which pipe the load rod passes.

The mill vane 8 is journaled at 9 upon the mill head to swing about an upright axis, the vane being moved toward and from the wind wheel when the latter is respectively to be placed out of and in the wind, spring buffers 10 cushioning the vane in the final portions of its swinging movements. 85

A swinging arm 11 is afforded an upright 90 axis of movement by being mounted upon a vertical bearing shaft 12 fixed upon the mill head with the load rod between and preferably substantially equidistant from the mounting shafts 9 and 12. The long 95 branch of arm 11 is flexibly connected with one end of link 13 whose other end moves a finger 13', operatively forming a part of the link, which operates to engage and move the vane toward the wheel in the furling operation, but from which finger the vane may move toward the wheel in governing. A lever rod 14 connects a vertically movable furling collar 15 with the arm 11 near the connection of said arm with link 13, which 100 link is also preferably a rod. The vane

shaft 9 is located between the vane ends of rods 13 and 16 that afford flexible connection between the furling collar 15 and the outer ends of an arm 8' pivoted between its 5 ends upon upright shaft 9. In the furling operation, link 13 pulls upon one end of arm 8' and rod 16 pushes upon the other end of this arm to cause finger 13' to push the vane 8 to a closed position. The lower ends 10 of lever rods 14 and 16 are bent to extend horizontally there to be journaled in horizontal bearings 17 formed on top of the furling collar 15 and on opposite sides of its axis and equidistantly from its center. The 15 collar 15 is in assembly with a sleeve 18 (loosely surrounding pipe 7), having connection with the upper ends of push rods 19 whose lower ends are connected with one end of a lever 20 whose other end carries 20 a pull wire 21 accessible from the ground. The collar 15 and the rods 14 and 16 will turn with the head and with reference to sleeve 18 which is only vertically movable. When the wire 21 is pulled downwardly 25 (after which action it is hooked at its lower or ground end), the rods 19 are consequently pushed upwardly to cause the sleeve 18 to push the furling collar up, to swing the mill vane from its position when the wheel is in 30 the wind to a position in which the wheel is out of the wind. The furling collar has a tubular continuation or elongation 15' and its supporting sleeve has a tubular elongation 18' within and extending upwardly beyond the elongation 15', both elongations 35 surrounding the column 7. The sleeve continuation prevents the sleeve from gripping the column. The collar is radially and horizontally extended beyond the horizontal or 40 shoulder portion of the sleeve, as indicated at 15°. An inverted annular channel 15'', constituting a hood, is formed around and in the bottom of the collar. The bottom portion of the collar between this channel 45 and the bore of the collar is received in an annular trough 22 which surrounds the column 7. This trough may be substantially stationary by having frictional engagement with the sleeve 18 upon the horizontal or shoulder portion of which the trough rests. By reason of the oil or other lubricant in 50 the trough such trough is constituted an antifriction step or end thrust bearing for the collar and the load upon the collar. The outer peripherally grooved hood portion 55 15'' of the collar cooperates with the outer annular rim of the trough to prevent seepage of moisture inwardly between the collar and its bearing and between the collar and the sleeve. The inner annular rim 60 of the trough guards against the outward horizontal seepage of moisture between the collar and its direct support—the bottom of the trough. Downward seepage of moisture 65 to the support for the collar is guarded

against by the annular hood 23 which is carried by the sleeve and is curled outwardly over and receives the upper end of the upright collar extension 15'. This hood has an upright downwardly extending tubular continuation 23' which surrounds the upwardly extending upright tubular continuation 18' of the sleeve, and is surrounded by the upwardly extending upright tubular continuation 15' of the collar. The hood 23 and its said extension are spaced apart from the upright collar portion 15' and the upright sleeve portion 18' to afford ample clearance permitting relative movement between the collar and sleeve. The sleeve is laterally spaced apart from the column to permit movement of the sleeve and the parts thereon laterally of the column. The hood extension may be made of sheet metal spun, at its lower end, into a unit with the inner 75 80 85 annular rim of the trough further to guard against the admission of moisture to the trough.

It is believed that the advantages of my invention will be fully realized from the 90 drawings and description which have been furnished.

It is obvious that changes may be made without departing from the spirit of my 95 invention.

Having thus described my invention I claim as new and desire to secure by Letters Patent the following:

1. Furling mechanism for a windmill 100 vane that has an upright column and a head mounted to turn upon the column, including a rotatable collar in furling connection with the vane and surrounding the column and an annular trough also surrounding the column and upon whose bottom the collar is supported; and a hood united with the inner 105 rim of the trough and extending upwardly from the trough within the collar and thence outwardly over the top of the collar.

2. Furling mechanism for a windmill 110 vane that has an upright column and a head mounted to turn upon the column, including a rotatable collar in furling connection with the vane and surrounding the column; an annular trough also surrounding the column and upon whose bottom the collar is supported; and a sleeve upon which the trough is provided and having an upwardly extending tubular continuation 115 which is surrounded by said hood.

3. Furling mechanism for a windmill 120 vane that has an upright column and a head mounted to turn upon the column, including a rotatable collar in furling connection with the vane and surrounding the column 125 and an annular trough also surrounding the column and upon whose bottom the collar is supported; a hood united with the inner rim of the trough and extending upwardly from the trough within the collar and 130

thence outwardly over the top of the collar; and a sleeve upon which the trough is provided and having an upwardly extending tubular continuation which is surrounded by said hood.

4. Furling mechanism for a windmill vane that has an upright column and a head mounted to turn upon the column, including a rotatable collar in furling connection with the vane and surrounding the column and an annular trough also surrounding the column and upon whose bottom the collar is supported; and a hood united with the inner rim of the trough and extending upwardly from the trough within the collar and thence outwardly over the top of the collar, this hood being laterally spaced apart from the collar.

5. Furling mechanism for a windmill vane that has an upright column and a head mounted to turn upon the column, including a rotatable collar in furling connection with the vane and surrounding the column and an annular trough also surrounding the column and upon whose bottom the collar is supported; and a hood united with the inner rim of the trough and extending upwardly from the trough within the collar and thence outwardly over the top of the collar, this hood being laterally spaced apart from the collar and from the column.

6. Furling mechanism for a windmill vane that has an upright column and a head mounted to turn upon the column, including a rotatable collar in furling connection with the vane and surrounding the column and an annular trough also surrounding the column and upon whose bottom the collar is supported; and a sleeve upon which the trough is provided and having an upwardly extending tubular continuation which is surrounded by said hood, the tubular continuation of the sleeve and said hood being laterally spaced apart from each other and from the collar and column.

7. Furling mechanism for a windmill vane that has an upright column and a head mounted to turn upon the column, including a rotatable collar in furling connection with the vane and surrounding the column and upon whose bottom the collar is supported; a hood united with the inner rim of the trough and extending upwardly from the trough within the collar and thence outwardly over the top of the collar, this hood being laterally spaced apart from the collar; and a sleeve upon which the trough is provided and having an upwardly extending tubular continuation which is surrounded by said hood, the tubular continuation of the sleeve and said hood being laterally spaced apart from each other and from the collar and column.

8. Furling mechanism for a windmill

vane that has an upright column and a head mounted to turn upon the column, including a rotatable collar in furling connection with the vane and surrounding the column; and an antifriction bearing in supporting relation to the collar.

9. Furling mechanism for a windmill vane that has an upright column and a head mounted to turn upon the column, including a rotatable collar in furling connection with the vane and surrounding the column; an antifriction bearing in supporting relation to the collar; and an annular hood extending over the top of the collar.

10. Furling mechanism for a windmill vane that has an upright column and a head mounted to turn upon the column, including a rotatable collar in furling connection with the vane and surrounding the column; and a sleeve upon which the collar is mounted to turn, said collar carrying an annular hood in shielding relation to the peripheral underlying portion of the sleeve.

11. Furling mechanism for a windmill vane that has an upright column and a head mounted to turn upon the column, including a rotatable collar in furling connection with the vane and surrounding the column; and a sleeve upon which the collar is mounted to turn, said collar carrying an annular hood in shielding relation to the peripheral underlying portion of the sleeve which carries a rim entering this hood.

12. Furling mechanism for a windmill vane that has an upright column and a head mounted to turn upon the column, including a rotatable collar in furling connection with the vane and surrounding the column; a sleeve in supporting relation to the collar; and an annular hood carried by the sleeve and extending outwardly over the top of the collar.

13. Furling mechanism for a windmill vane that has an upright column and a head mounted to turn upon the column, including a rotatable collar in furling connection with the vane and surrounding the column; a sleeve in supporting relation to the collar; an antifriction bearing between the bottom of the collar and the sleeve; and an annular hood carried by the sleeve and extending outwardly over the top of the collar.

14. Furling mechanism for a windmill vane that has an upright column and a head mounted to turn upon the column, including a rotatable collar in furling connection with the vane and surrounding the column; a sleeve in supporting relation to the collar; an annular hood carried by the sleeve and extending outwardly over the top of the collar; and an annular hood carried by the collar in shielding relation to the peripheral underlying portion of the sleeve.

15. Furling mechanism for a windmill vane that has an upright column and a head

mounted to turn upon the column; a rotatable collar in furling connection with the vane and surrounding the column; a sleeve in supporting relation to the collar; an anti-friction bearing between the bottom of the collar and the sleeve; an annular hood carried by the sleeve and extending outwardly

over the top of the collar; and an annular hood carried by the collar in shielding relation to the peripheral underlying portion of 10 the sleeve.

In witness whereof, I hereunto subscribe my name.

DANIEL R. SCHOLES.
